UNITED STATES PATENT OFFICE.

GIUSEPPE PAVIA, OF ALLENTOWN, PENNSYLVANIA.

SHUTTLE.

No. 876,085.

Specification of Letters Patent.

Patented Jan. 7, 1908.

Application filed March 6, 1906. Serial No. 304,444.

To all whom it may concern:

Be it known that I, GIUSEPPE PAVIA, a subject of the King of Italy, residing in Allentown, county of Lehigh, State of Pennsylvania, have invented certain new and useful Improvements in Shuttles; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 My invention is an improvement in shuttles for looms weaving broad goods, and it relates particularly to the construction of the bobbin skewer or spindle and its accessory parts. In shuttles of this kind at present in 20 use, the pivoted skewer or spindle is impinged against on an angular face thereof by a bent plate-spring held in position by several pins mounted in the walls of the shuttle and traversing the bobbin chamber near one end 25 thereof.

My objects, among others, are to reduce the expense of materials and labor incident to the manufacture of shuttles with respect to the parts above referred to and to so construct and arrange the same as to avoid any 30 possibility of splitting the shuttle, as is now sometimes the case in the use of the spring aforesaid, and insure against the shuttle being placed in the loom with the skewer not 35 fully depressed, as also sometimes now occurs when the parts become worn or weak.

I have illustrated my invention in two views in the accompanying drawings, wherein,

40 Figure 1 is a plan view of the improved shuttle; and Fig. 2 is a side view thereof, showing the near wall partly broken away.

45 *a* is the shuttle, *b* its bobbin chamber, and *c* the usual bobbin-skewer or spindle; *d* is the bobbin or cop arranged on said skewer.

The body or pivot part *e* of the spindle or skewer *c* is fulcrumed on the pivot pin *f* which traverses the bobbin-chamber *b*, and it has the usual lug *g* adapted to take up against a 50 shoulder *h* in the bottom of said chamber when the spindle is in its proper depressed position in the shuttle. On one side of said

body or pivot part *e* (preferably the top side) is formed a lug *i*; otherwise this side is or may be substantially flat.

55

j is a recess forming an extension of the bobbin-chamber and disposed longitudinally at the pivot end of the skewer. In this recess is arranged a catch *o* extending longitudinally of the shuttle and preferably in the form of a lever fulcrumed between its ends on a pin *k* which traverses the recess. The inner end of this catch bears against the body or pivot part *e* of the skewer and it is formed with a notch *l* adapted to receive the lug *i* of 65 said body or pivot part when the skewer is in the depressed position, as shown, at which time it holds the skewer positively against movement on its pivot. Under the outer end of said catch is a coiled spring *m* set in a 70 socket *n* in the bottom of the recess *j* and acting to press the said outer end of the catch upwardly, whereby to preserve contact between the catch and the body or pivot part *e*.

In order to raise the spindle or skewer, the 75 outer end of the catch is depressed by the finger until the lug *i* and notch *l* clear each other. When the skewer or spindle is depressed, the spring causes the catch to snap into position, bearing squarely against the 80 top face of the body or pivot part *e*, as soon as the lug and notch coincide with each other, in which position the skewer will be locked firmly in the depressed position.

Having thus fully described my invention 85 what I claim as new and desire to secure by Letters Patent is:

The combination of a shuttle body having a bobbin chamber and a recess forming a longitudinal extension of said chamber and opening upwardly through the top of said shuttle body, a bobbin spindle fulcrumed in said body, a substantially horizontal catch fulcrumed between its ends in said recess and having one end bearing on the butt or the 90 spindle, the material of the shuttle body being extended intact under said recess and thus forming the bottom wall of said recess and being formed with a shoulder having one 95 face at right angles to the closed position of the spindle, and a spring interposed between the other end of the said catch and the bottom wall of said recess, said catch and the spindle having the one a lug and the other a 100

notch engageable with each other to lock the spindle against pivotal movement and said spindle having a downwardly projecting lug adapted to engage said face of the shoulder 5 when the spindle is locked down by the catch, substantially as described.

In testimony that I claim the foregoing, I

have hereunto set my hand this 3rd day of March, 1906.

GIUSEPPE PAVIA.
